UNITED STATES PATENT OFFICE.

SAMUEL TRETHEWEY, OF PITTSBURG, PENNSYLVANIA, ASSIGNOR TO THE TRETHEWEY MANUFACTURING COMPANY, OF SAME PLACE.

ROTARY SHEARS.

SPECIFICATION forming part of Letters Patent No. 479,037, dated July 19, 1892.

Application filed June 30, 1891. Serial No. 398,028. (No model.)

To all whom it may concern:

Be it known that I, SAMUEL TRETHEWEY, a resident of Pittsburgh, in the county of Allegheny and State of Pennsylvania, have invented a new and useful Improvement in 5 Rotary Shears; and I do hereby declare the following to be a full, clear, and exact description thereof.

My invention relates to rotary shears, its 10 object being to provide a form of apparatus which may be readily adjusted for cutting sheets, plates, bars, &c., to different lengths, and one which provides a convenient form of carriage for feeding the sheets, plates, bars, 15 &c., to the shears.

To enable others skilled in the art to make and use my invention, I will describe the same more fully, referring to the accompanying drawings, in which—

20 Figure 1 is a side view, Fig. 2 a plan view, and Fig. 3 a detail sectional view, of one of the lower cutter-shafts, showing the manner of retaining the cutter securely in place. Fig. 4 is a section on the line 4-4, Fig. 3; and Fig. 25 5 is a view of the wedge employed.

Like letters indicate like parts.

The bed or frame A, which supports the apparatus, is composed of the horizontal side beams *a* and the end cross-beams *a'*, the said 30 bed or frame resting on the underlying beams *a²*. Journaled in suitable bearings in the end cross-beams *a'* of the bed A is the main shaft *b*. In order to impart a rotary movement to said shaft *b*, a power-shaft *c* is situated adjacent to the bed A, said power-shaft being journaled in bearings in the standards *d*. A tight 35 and loose pulley *e* is mounted on the power-shaft *c* and is adapted to be driven by any suitable power. A pinion *f* is secured to the 40 power-shaft *c* and meshes with the large gear-wheel *g* on the main shaft *b*. On the main shaft *b*, just beyond the large gear-wheel *g*, is the pinion *h*, which meshes with a pinion *i* on the lower shaft of the two cutter-shafts *j* 45 *j'* of the stationary rotary shears B. The stationary shears B are bolted or otherwise secured to the bed A, and they are composed of the upper and lower arms *k* *k'*, which extend out from the body portion *k²*, the said arms *k* *k'* forming between them the slot *l*. This slot

permits of the entrance of the ends of sheets, plates, bars, &c., which extend beyond the cutters during the cutting operation. The cutter-shafts *j* *j'*, arranged the one above the other, are journaled in suitable bearings in 55 the body portion *k²* and in the arms *k* *k'* of the stationary shears B. On the outer ends of the cutter-shafts *j* *j'* are secured the cutters *m* *m'*, circular in form and provided with cutting-edges. To provide for the vertical adjustment of the cutters *m* *m'* to and from each other, I prefer to have the cutter-shafts *j* *j'* journaled in accordance with the construction set forth in Letters Patent No. 429,072, granted to me May 27, 1890. To prevent any 60 play of the lower cutter *m'* and consequent displacement thereof with relation to the upper cutter *m* during the cutting operation, I provide the wedge *n*, adapted to enter a suitable wedge-shaped slot or seat formed in the 65 lower arm *k*. This wedge *n* when in position is adapted to bear against the flange *n'* on the inner end of the bushing *o*, as illustrated in Fig. 3, and said wedge is retained therein by the nut *n²*, engaging with the threaded neck *n³* 70 of said wedge. Since the cutter *m'* is held on the shaft *j'* by the nut *p*, it is apparent that as the wedge *n* is forced into the seat formed to receive it it will act through the flange *n'* to drive back the bushing *o*, bringing a 75 pressure to bear on the plate *p'* on the inner end of the shaft *j'*, thereby, through the nut *p* on the outer end of said shaft, drawing back the cutter *j'*. This will prevent any longitudinal play or wabbling on the part of 80 said cutter *m* on the shaft *j* and will insure the perfect vertical adjustment of said cutter, and consequently an even regular cut.

As hereinbefore stated, the pinion *h* meshes with the pinion *i* on the lower cutter-shaft *j'*, 85 and thus provides for the rotation of said shaft *j'*. To impart a like rotary movement to the upper cutter-shaft *j*, the pinion *i* meshes with the pinion *q* on the said cutter-shaft *j*. A hanger or bracket *q'* projects out over 90 the upper arm *k*, and in said hanger is journaled the idle-roller *q²*, said roller being arranged at such height as to press on the upper surface of the sheets, plates, bars, &c., to be cut as they pass between the cutters. This 95 100

roller q^2 serves to prevent any tendency on the part of the sheets, plates, or bars to rise during the cutting operation.

The adjustable shears C are situated on the bed A opposite the stationary shears B, and as the construction of the said adjustable shears is exactly similar to that of the stationary shears the same letters of reference and description as applied thereto are applicable with reference to the adjustable shears C. Power to operate the cutter-shafts of the adjustable shears C is obtained in the same manner from the main shaft b.

The adjustable shears C are mounted in suitable guideways in the bed A, and to provide for the adjustment of said shears C at different positions on the bed A with relation to the stationary shears B the frame of the adjustable shears is constructed with the hanger r, in which is journaled a pinion r'. The pinion r' engages with the rack s on the bed A, said pinion being operated by a hand-wheel r², whereby upon the rotation of said hand-wheel the adjustable shears C may be made to approach and withdraw from the stationary shears B. Any other convenient form of mechanism for moving the adjustable shears C may, however, be employed.

The track t is supported on the frame A between the stationary and adjustable shears and is provided with the rails t', upon which the wheels of the table or carriage u are adapted to travel. The track t is arranged parallel with the line of the cutting and may be moved, together with the carriage u, to or from the stationary shears B, according to the lengths of the sheets, plates, or bars to be cut.

To support the portions of the sheets, plates, or bars adjacent to the cutters during the cutting operation and prevent their sagging, idle-rollers v v' are employed. These rollers v v' are journaled in suitable standards of sufficient length to bring the tops of the rollers even with the top of the lower cutters, as well as even with the top of the carriage u. The roller v' may be secured at any position between the stationary and rotary shears as the adjustable shears C are brought nearer or withdrawn farther from the stationary shears.

The operation of my improved rotary shears is as follows: By turning the hand-wheel r² in the proper direction the adjustable shears C are brought to the proper position relative to the stationary shears B, according to the lengths of sheets, bars, or plates to be cut. The carriage u and the idle-roller v' are also brought to like positions relative to the lengths of the sheets to be cut. The cutters themselves having been adjusted properly, power is then applied to rotate the power-shaft c,

whence power is transmitted through the connections described to operate the cutter-shafts j j' of the stationary and adjustable shears at a uniform rate of speed. The sheets, plates, or bars, whether in packs or singly, are placed upon the carriage u, when said carriage is moved along the track t to bring the ends of the sheets, plates, or bars between the cutters m m', the idle-rollers v v' acting to support same adjacent to the point of cutting, and thereby preventing any sagging on the part of the sheets, plates, or bars, and so insuring an even and regular cut. At the same time the idle-rollers q² press on the upper surface of the sheets as they pass between the cutters and prevent any upward movement on the part of said sheets. In case the lower cutters m' become loose on the cutter-shafts, it is only necessary to tighten the nut n² on the end of the wedge n, when said wedge, in the manner hereinbefore described, will prevent any wobbling of the cutters and will retain them in a perfect vertical position.

By the above construction I obtain double-headed rotary shears, which may be adjusted for cutting sheets, plates, bars, &c., to different lengths, greatly decreasing the time and labor of shearing.

What I claim as my invention, and desire to secure by Letters Patent, is—

1. In rotary shears, the combination, with a bed or frame, of cutter-shafts journaled therein, cutters secured to said shafts, and a bracket projecting out over the upper cutter and having a depending arm carrying a roller, said roller being adapted to press upon the upper face of the sheet, plate, &c., being cut, substantially as and for the purposes set forth.

2. In rotary shears, the combination, with the frame, of cutter-shafts journaled therein, the one above the other, and a wedge-shaped key engaging a flange on a bushing surrounding the lower cutter-shaft, said key acting to force back the said cutter-shaft and prevent any longitudinal movement on the part of the cutter secured thereto, substantially as and for the purposes set forth.

3. In rotary shears, the combination, with the frame, of the lower cutter-shaft j', a bushing o, having the flange n', the wedge n, the plate p, secured to the shaft j', the cutter m', and nut p', substantially as and for the purposes set forth.

In testimony whereof I, the said SAMUEL TRETHEWEY, have hereunto set my hand.

SAMUEL TRETHEWEY.
